UNITED STATES PATENT OFFICE.

PETER STEIGER, OF BALTIMORE, MARYLAND.

TRUNK.

SPECIFICATION forming part of Letters Patent No. 772,682, dated October 18, 1904.

Application filed April 2, 1904. Serial No. 201,229. (No model.)

To all whom it may concern:

Be it known that I, PETER STEIGER, a citizen of the United States, residing at Baltimore, State of Maryland, have invented certain new and useful Improvements in Trunks, of which the following is a specification.

My invention relates to improvements in tray-supports for trunks of that class in which the tray may be elevated from within the body of the trunk simultaneously with the raising of the trunk-lid.

The present invention, however, relates more particularly to that feature or construction of the device by means of which the tray and lid may be elevated simultaneously or, if desired, the lid may be elevated independently of the tray.

The invention is illustrated in connection with a construction of tray-elevating mechanism which is the subject of a pending application filed by me on October 30, 1903, and with which the present invention is preferably combined; but it is to be understood that the features of the present invention may be readily combined with other tray-operating mechanisms.

The invention is illustrated in the accompanying drawings, in which—

Figure 1 illustrates a perspective view of a trunk embodying my invention and shows the lid and tray in the elevated position. Fig. 2 illustrates a perspective view of the detached elevating mechanism, but with its several parts in the proper positions with respect to each other during the operation of elevating the lid independently of the tray. Fig. 3 illustrates a sectional elevation of the trunk box and lid, the latter being partly elevated, and an end elevation of the tray supporting and lifting mechanism. Fig. 4 illustrates a sectional elevation through the trunk box and lid, the latter being elevated, and also shows an end elevation of the tray in the raised position. Fig. 5 illustrates a vertical sectional detail, on a large scale, of a portion of the trunk box and lid when the latter is closed and shows the relative position of the tray and its supports and elevating mechanism. Fig. 6 illustrates a modified form of lid-operating lever.

In the drawings, A designates the trunk-box, having end walls *a*, and A' designates the lid, having the end walls *a'*. The box and lid may vary in construction, according to the price and taste of the manufacturer. 55 Pivoted on the interior of the box and to each of the end walls *a* are two levers *b*, and the other ends of these levers are pivotally connected to horizontal bars *c*, so that said levers and bars may all swing together. The 60 bars *c* are each provided at their outer vertical sides with a plurality of horizontally or laterally projecting lugs *d*, which latter project and rest upon the top edge of the trunk-box A when the lid is closed. These lugs *d*, 65 as will be seen in the drawings, are preferably near the ends of the horizontal bars and have position on opposite sides of a vertical arm *b'*, also on said bar. A link *e* is pivotally connected at one end to the vertical arm 70 *b'* and at its other swinging end is provided with a laterally-projecting pin *h*, for a purpose to be presently described.

The tray F is provided along its opposite ends with a horizontal plate *f*, which has at 75 its upper edge a downwardly-projecting hook-flange *f'*, which latter takes over the top edge of the horizontal bar *c*, so that said bar will entirely support the tray without the aid of additional supports commonly used within 80 the body of the trunk for the tray to rest upon when the lid is closed.

The end walls *a* of the trunk-box are each provided in the present instance with a plurality of notches *g*, which receive the lugs *d* 85 when the tray and bar *c* are lowered, and when the lid is closed down on the trunk-box these lugs have position between the tray and box and entirely support the tray within the said box. 90

A plate I, preferably of angle-iron or L shape and having the vertical wall *i* and the lateral wall *i'*, is secured to the lid of the trunk, so that the wall *i'* will take beneath the end walls *a'* of the lid, while the vertical 95 wall *i* will take against the inner surface of said end wall *a'*, as clearly seen in Fig. 5. This plate I is provided with a longitudinal slot *j*, which extends in a direction parallel with the lower edge of the trunk-lid, and at 100

- its forward end said plate is provided with a downwardly-projecting notch *k*, which extends from said slot toward the lateral wall *i'* of the plate. The pin *h* of the link *e* projects 5 through the slot *j* and when the lid is down rests in the notch *k*. A groove *l* is provided in the wall *a'* of the lid adjacent the plate *I*, and the pin *h* takes in said groove and has longitudinal movement therein.
- 10 The link connecting the vertical arm *b'* with the lid need not necessarily be of one piece, but may have an additional link *e'*, pivotally connecting it with said lid. This latter form of link is illustrated in Fig. 6.
- 15 The operation is as follows: When the tray is in position with the trunk-box and the lid is closed, the pin *h* of the link *e* has position in the downwardly-projecting notch *k* of the plate *I*, and as long as it remains in said 20 notch the raising of the lid will cause the simultaneous elevation of the tray, because the notch serves as a pivot-point for the pin *h* to turn in and prevents the pin moving through the slot *j*. It will thus be seen that the tray 25 and lid will be elevated together, as seen in Figs. 1 and 4 of the drawings. If it is desired to elevate the lid only and leave the tray in a stationary position, the lid is first elevated slightly, as shown in Fig. 3, and the 30 hand of the operator is inserted beneath the lid, and the links *e* are raised so as to elevate the pins *h* from the notches *k*. As soon as the pins are disengaged from said notches the lid may then be farther elevated and the pins 35 will slide through the slots *j* of the plate *I*, as seen in Fig. 2, and the links *e* will merely turn on their ends, which are pivotally connected to the vertical arms *b'*, without elevating the tray.
- 40 It will thus be seen that the present construction enables the lid and tray to be elevated simultaneously or the lid to be raised independently of the tray. It will also be seen that the tray may be supported entirely 45 from the top edge of the trunk-box without the aid of stationary supports on the interior of the box and also that the tray may be readily raised from its movable supports and lifted out of the trunk entirely. It will also be 50 seen that by pivoting the link *e* to a vertical arm *b'* the lid may be elevated slightly without elevating the tray even while the pin *h* is engaged in the notch *k*, and that this inde-

pendent movement is enough to permit the insertion of the hands, so that the links may 55 be operated to disengage the pins from said notches.

Having thus fully described my invention, what I claim as new, and desire to secure by Letters Patent, is—

1. The combination with the box of a trunk; a lid hinged to said box; a movable tray-support; a single link movable at all times with the lid and connecting the tray-support and means whereby the link may be elevated with 65 the lid independently of or simultaneously with the tray-support and arranged to hold the lid when the latter is elevated.

2. The combination with the box of a trunk; a lid hinged to said box; a tray-support pivotally connected to said trunk-box; a link pivotally connected at one end to said tray-support, and means for either pivotally or slidably connecting the other end of said link with the trunk-lid.

3. The combination with the box of a trunk; a lid hinged to said box; a movable tray-support; a link pivotally connected at one end to said tray-support; a plate secured to said lid and provided with a notch in which the free 80 end of the link will engage.

4. The combination with the box of a trunk; a lid hinged to said box; a movable tray-support; a plate secured to said lid and having a slot and also having a notch at one side of 85 said slot, and a link pivotally connected at one end to said tray-support and having its other end secured in the slot of said plate whereby the lid may be raised independently of or simultaneously with the tray-support.

5. The combination with the box of a trunk; a lid hinged to said box; a movable tray-support; an arm projecting above said support; a plate secured to said lid and having a slot and also having a notch at one end of said 95 slot, a link pivotally connected at one end to the projecting arm of said support and having its other end secured in said slot whereby the lid may be raised independently of or simultaneously with the tray-support.

In testimony whereof I affix my signature in presence of two witnesses.

PETER STEIGER.
